PRESS STRUCTURE

Filed Sept. 25, 1943

UNITED STATES PATENT OFFICE

2,428,620

PRESS STRUCTURE

Walter Ernst and Richard M. Norman, Mount Gilead, Ohio, assignors to H-P-M Development Corporation, a corporation of Delaware

Application September 25, 1943, Serial No. 503,820

1 Claim. (CL 100—71)

1

This invention relates to press structures.

An object of the invention is to provide a press structure wherein pressing forces are arranged angularly with respect to one another so that the pressing forces tend to hold the press structure together.

Another object of the invention is to provide a press structure wherein a plurality of rams operate angularly with respect to one another, and wherein the press structure is interlocked in such a manner that the pressing forces developed by the rams increase the pressure between the locking surfaces of the structure.

Another object of the invention is to provide a press structure wherein the press head and press base are dovetailed together through means of dovetail joints on uprights positioned between the press head and press base, and wherein the uprights of the press structure form the press head and press base of a press that operates angularly to the first mentioned press head and press base.

Still another object of the invention is to provide a press structure in accordance with the foregoing object wherein one of the presses is a vertical acting press while the uprights function as the elements of a horizontal acting press.

Still another object of the invention is to provide a more rigid press structure that will substantially eliminate the misalignment of the press frame wherein the press is provided with rams acting angularly with respect to one another.

Further objects and advantages will become apparent from the drawings and the following description.

In the drawings:

Figure 1 is a front elevational view of a press constructed in accordance with the invention, having a part thereof broken away to illustrate a connecting tie or strain rod.

Figure 2 is a side elevational view of the press structure illustrated in Figure 1.

In this invention the press structure consists of a press base 10 and a press head 11. The press head 11 is provided with a dovetail recess 12 that extends across the bottom surface 13 of the press head 11. The press base 10 is provided with a similar dovetail recess 14 that extends across the upper surface 15 of the press base 10.

The press head 11 and the press base 10 are connected by means of vertical uprights or side members 16 and 17 that are substantially solid members extending across the depth of the press head and base, as illustrated in the side view of Figure 2. The upright 16 is provided with a co-operating dovetail connection 18 that engages

2

one side of the dovetail recess 12 in the press head 11, and with a similar dovetail connection 19 that engages one side of the dovetail recess 14 in the press bed 10. The upright 17 is provided with similar dovetail connections 18a and 19a that co-operate with the opposite side of the dovetail recesses 12 and 14, respectively.

It will thus be seen from Figure 1 that with the uprights 16 and 17 in position, the press head 11 and press base 10 will be interconnected and be spaced relatively to one another in suitable manner for providing a vertical acting press structure.

Tie rods or strain rods 20 extend through the press head 11, the uprights 16 and 17 and the press base 10 to secure the same together, suitable nuts 21 being provided on opposite ends of the strain rods 20 to retain the press structure together. The vertical tie rods 20 are preferably prestressed when the nuts 21 are tightened to a tonnage substantially greater than that which will be developed by the vertical acting press.

The press head 11 is provided with a conventional ram 22 that operates in a cylinder 23. The ram 22 may be of the single acting or double acting type as desired. The ram 22 thus moves vertically toward and away from the press bed 10 during reciprocation thereof when the ram is operated. A suitable fluid pressure system may be provided for supplying fluid under pressure to the cylinder 23 for hydraulically operating the ram 22.

The vertical upright 16 carries a cylinder 24 in which a ram 25 operates. The cylinder 24 is also suitably connected to the hydraulic system for the press for reciprocating the ram 25 therein. It is to be understood that any of the conventional hydraulic systems and controls for the same can be used to produce reciprocation of the rams 22 and 25 in their cylinders 23 and 24, respectively.

From the foregoing description it will thus be seen that the ram 22 is a vertical acting ram and that the ram 25 is a horizontal acting ram so that the forces applied by these rams to the press structure during operation thereof are at right angles to one another. In effect, therefore, the press structure has two heads consisting of the head 11 for the vertical acting ram 22 and the upright or head 16 for the horizontal acting ram 25. Similarly the press has two beds consisting of the bed 10 for the vertical acting ram 22 and the upright or bed 17 for the horizontal acting ram 25. With the forces of the two rams 22 and 25 acting angularly to one another, it will also

be apparent that the forces developed by the rams will tend to more tightly bind the dovetail connections between the uprights 16 and 17 and the recesses 12 and 14. The force tending to separate the head 11 from the bed 10 will be opposed by the force tending to separate the head 16 from the bed 17, the dovetail joints on the head upright 16 and the bed upright 17 being forced outwardly against the dovetail recesses 12 and 14. This thereby binds the dovetail surfaces together and provides for a very rigid construction.

A suitable support 26 can be provided for the purpose of supporting molds or dies of a suitable character that can be retained together by means of a pressure applied by the plunger 27 carried by the ram 25, the plunger 27 forcing the mold or die together against the support member 28. A suitable plunger or forming member 29 can be carried by the ram 22 to produce a work operation upon material placed within the mold or die held by the ram 25. It is, of course, understood that the type of work accomplished upon the press may be varied over a wide range depending upon the type of dies and plungers positioned in the press.

While the apparatus disclosed and described herein constitutes a preferred form of the invention, yet it will be understood that the device is capable of mechanical alteration without departing from the spirit of the invention, and that all such modifications as fall within the scope of the appended claim are intended to be included herein.

Having thus fully described our invention what we claim as new and desire to secure by Letters Patent is:

A multiple ram press that includes, a press head having a ram operable therein, a press bed, an upright on each side of said press extending

between said head and said bed, one of said uprights having a ram operable therein and movable in a direction toward the other upright and at right angles to the movement of the first ram, 5 strain rod means extending between said head and said bed for connecting the same and for carrying the thrust of said first ram, a dovetail recess in each of the confronting faces of said head and said bed providing inclined surfaces and surfaces which are perpendicular to the line of thrust of said first ram, said inclined surfaces being inclined angularly toward the central portion of the press, said uprights being each provided with a dovetail connection at each end 10 thereof providing inclined surfaces and surfaces which are perpendicular to the line of thrust of said first ram, the inclined surfaces of said head and bed being in engagement with the inclined surfaces of said uprights and said perpendicular surfaces of said head and bed being in abutting relationship with said perpendicular surfaces of said uprights, whereby the forces of the two rams acting angularly to each other will develop forces tending to bind tightly the dovetail connections 15 20 25 between said uprights and said bed and head.
